UNITED STATES PATENT OFFICE.

GEORGE H. DIPPO, OF CHAGRIN FALLS, OHIO, ASSIGNOR TO THE FERRO-STEEL COMPANY, OF CLEVELAND, OHIO.

DESIGN FOR A SAD-IRON.

SPECIFICATION forming part of Design No. 33,286, dated October 2, 1900.

Application filed March 28, 1900. Serial No. 10,552. Term of patent 14 years.

o all whom it may concern:

Be it known that I, GEORGE H. DIPPO, a citizen of the United States, and a resident of Chagrin Falls, county of Cuyahoga, and State of Ohio, have invented and produced a new and original Design for Sad-Irons, of which the following is a specification, reference being had to the accompanying drawing, forming a part thereof.

The figure represents a perspective view showing my new design.

The leading or material feature of my design consists of a body portion B of triangular form, such as is used in the construction of a flat-iron, combined with a handle A, consisting of a bow-shaped grip a and a transverse member a', connecting the ends of said grip, said ends being located near the upper surface of the body portion and respectively near the apex and the middle of the base, as shown, the transverse member being suitably secured to said upper surface, such body portion having a form hereinafter described. Said body portion B presents upon its lateral surface three parallel zones b, b', and b². Zone b is formed by a downwardly-projecting lateral portion of a plate, which is secured to the top of said body portion and whose lateral sur-

face is caused to be parallel, but depressed, with respect to the contiguous lateral surface 30 of the zone b', as shown, thereby forming a shoulder b³ between said two zones. Along the lower edge and parallel therewith is formed the zone b², whose surface, while parallel with the surface of zones b and b', 35 slightly projects, forming a short shoulder at the boundary contiguous to zone b'. Said zone b² is formed with angularly-formed upwardly-projecting portions at the corners of the body portion, as shown. The widths of 40 zones b and b' are made substantially equal; but that of each is less than that of zone b, so that two comparatively-narrow zones are formed with an intermediate wider zone, all these zones being parallel with each other 45 and the upper and lower surfaces of the body portions.

What I claim is—

The design for a sad-iron substantially as shown as described.

Signed by me this 21st day of March, 1900.

GEO. H. DIPPO.
